Primary Examiner — Omeed Agilee(74) *Attorney, Agent, or Firm* — Quarles & Brady LLP(57) **CLAIM**

The ornamental design for a pipette, as shown and described.

DESCRIPTION

FIG. 1 is an isometric view of a top, front, and left side of a pipette;

FIG. 2 is a front elevational view of the pipette of FIG. 1; FIG. 3 is a rear elevational view of the pipette of FIG. 1; FIG. 4 is a left side elevational view of the pipette of FIG. 1;

FIG. 5 is a right side elevational view of the pipette of FIG. 1;

FIG. 6 is a top plan view of the pipette of FIG. 1; and, FIG. 7 is a bottom plan view of the pipette of FIG. 1.

The dash-dash-dash broken lines are included for the purpose of illustrating portions of the pipette that form no part of the claimed design.

1 Claim, 5 Drawing Sheets(56)
